UNITED STATES PATENT OFFICE.

MARTIN RINKEL, OF ASHLEY, INDIANA.

STEAM-BOILER.

SPECIFICATION forming part of Letters Patent No. 637,034, dated November 14, 1899.

Application filed May 26, 1899. Serial No. 718,420. (No model.)

To all whom it may concern:

Be it known that I, MARTIN RINKEL, a citizen of the United States, residing at Ashley, in the county of Steuben and State of Indiana, have invented new and useful Improvements in Steam-Boilers, of which the following is a specification.

My invention relates to vertical water-tube steam-boilers; and its object is to provide an improved construction of the same by which I secure a constant circulation of the water, thus purifying the same and at the same time effecting a saving in the quantity of fuel consumed.

15 The invention consists in the novel construction and combination of parts hereinabove fully described and claimed.

In the accompanying drawings, Figure 1 is a central vertical section of a steam-boiler 20 constructed in accordance with my invention. Fig. 2 is an elevation of the inner shell of the boiler disconnected from the outer shell. Fig. 3 is a plan view of the same.

In the said drawings the reference-numeral 25 1 designates the outer shell of the boiler, to the lower end of which is bolted an inwardly and upwardly extending curved flange 2, which supports the grate-bars 3. Said shell is formed with the usual fuel-opening 4 and 30 door 5. Connected with the upper end of the said shell are a smoke-box 6 and stack 7.

The numeral 8 designates the inner section 35 of the boiler, composed of three sections 9, 10, and 12, the central section 10 being bolted to the upper and lower sections 9 and 12, respectively. The lower end of the lower section is bolted to the said flange 2, while the upper end of the section 9 is bolted to a circular plate 13, located below the top 40 14 of the outer section 1, and is suspended from the said top by means of vertical rods 15. The space between said inner and outer shells forms a water-space, while the upper end of the outer shell serves as a steam and 45 water space or chamber. The numeral 16 designates a steam-pipe connected with said steam-space, and 17 a manhole-cover. It will be seen that the said inner section 10 is in the form of an inverted truncated cone and 50 is provided with openings 18, communicating with the water-space between the shells.

Connected with these openings are the curved lower ends of circulating-pipe 19, which are located within the inner shell. The other or body portions of said tubes are extended 55 vertically upward and communicate with the water-space above the circular plate 13. The space between said tubes forms a smoke space or chamber for the smoke and unconsumed products of combustion arising from 60 the fire-chamber, and near the upper end of the section 9 are flues 20, communicating with said smoke space or chamber and the smoke-box.

The operation is as follows: The space between the said shells is filled with water and a fire built on the grate. The heat will ascend and pass around the tubes located in the inner shell, which will rapidly heat the water and convert it into steam. This will cause 70 the water to constantly circulate through the tubes and water-space, thus effecting a saving in fuel consumed and also purifying the water.

It will be seen that the smoke-box 6 is of 75 larger diameter than the boiler, so that there will be a space therebetween, with which the flues 19^a communicate.

Having thus fully described my invention, what I claim is—

In a vertical water-tube steam-boiler, the combination with the outer shell, the inverted truncated conically-shaped steam-chamber at the upper end thereof, and the smoke-box of a greater diameter than that of the casing 85 and fitting over the upper end thereof, of the inner sectional shell, the central portion of which is in the form of an inverted truncated cone, the circular plate at the upper end of said inner shell, the vertical tubes located in 90 said inner shell having their lower ends curved and communicating with the space between said shells, and the flues at the upper end of said inner shell communicating with the smoke-box, substantially as described. 95

In testimony whereof I have hereunto set my hand in presence of two subscribing witnesses.

MARTIN RINKEL.
